UNITED STATES PATENT OFFICE.

T. G. THOMPSON, OF RICHMOND, AND A. E. FOX, OF GREENSBOROUGH,
ASSIGNORS TO THOMPSON, BALLARD & CO., OF RICHMOND, INDIANA.

IMPROVEMENT IN HAND-LOOMS.

Specification forming part of Letters Patent No. 69,047, dated September 17, 1867.

To all whom it may concern:

Be it known that we, T. G. THOMPSON, of the city of Richmond, in the county of Wayne and State of Indiana, and A. F. FOX, of the town of Greensborough, in the county of Henry and State of Indiana, have invented a new and useful Improvement in Self-Acting Hand-Looms, of which the following is a full, clear, and exact description, reference being had to the accompanying drawings, which are made a part of this specification.

Our invention belongs to the class of self-acting hand-looms; and consists of a latch-bar operated by the batten of the loom, a cam provided with stops and inclined surfaces, and a carrier which is caused to bear upon the inclined surfaces, said carrier being secured to the trip which depresses the treadles and gives motion to the harness; also of a hinged handle secured to the center of the front surface of the batten, by means of which the machine is put in motion; and also of a continuous spring secured to the under side of the batten and connecting with the triggers.

Figure 1 is a perspective view of our improved self-acting hand-loom. Fig. 2 is a transverse section of the batten and elevation of the latch-bar and cam which give motion to the finger-bar for depressing the treadles. Fig. 3 is a plan of the batten and warp-protector attached thereto, and the latch-bar, cam, carrier, finger-bar, and treadles. Fig. 4 is a perspective view of the latch-bar, cam, and carrier. Fig. 5 is an elevation of the guide to the ratchet-bar, the ratchet-wheel, and pawl which give motion to the cloth-roller. Fig. 6 is a plan of the under side of the batten, showing the continuous spring, the trigger, and picker-bar.

A is the frame of the loom. B is the batten, in general form the same as those now in use. a are the posts of the batten, pivoted to the lower rail of the frame A.

To one of the posts a is secured the adjustable guide b, consisting of a strip of metal or wood, having longitudinal slots b' in each end, through which screws b'' pass into the post a.

The inner side of the adjustable guide b is cut out sufficiently to allow the ratchet-bar c

to move freely between the guide and post. This bar carries the pawl d, engaging the ratchet-wheel e, secured to the cloth-roller f.

The front wall of each shuttle-box g is slotted, and has pivoted in it the retaining-block h.

A rod, i, is held in suitable bearings in front of the batten, and extends from one shuttle-box g to the other. The ends of the rod are provided with compressing-levers k. They are caused to bear upon the retaining-blocks h by the springs l.

At or near the center of the rod i is secured the detaining-arm m, projecting toward the front, which arm impinges upon the block n, attached to the beam n', when the shuttle is not properly boxed.

Beneath the block n is the recess n'' in the beam n', into which the detaining-arm enters when the shuttle is properly boxed.

The post a of the batten gives motion to the latch-bar C, which passes through the slide-box o, attached to the upper longitudinal rail of the frame A of the loom. This bar is guided in its reciprocating motion by the slide-bar o', secured to the frame A between the slide-box o and the beam n'.

The front end, p, of the latch-bar C is turned inward at right angles, and the pin q is secured to and projects inward from the latch-bar C, at such a distance from the end p of the bar as will permit the necessary motion back and forth of the post a of the batten.

A hook, r, upon the under side of the latch-bar, near its inner end, engages the pins s', projecting from the ratchet-cam s, which is journaled on a stud attached to the frame A.

A carrier, D, bears upon the ratchet-surfaces of the cam s. It is attached in a secure manner at one end to the finger-bar E. The finger-bar E is pivoted in the rotating post t, pendent from the beam n'.

A spring, t', made fast to the post t and beam n, by its elasticity causes the finger-bar E to constantly press the carrier D upon the face of the ratchet-cam s. The liberated end of the finger-bar E presses down alternately the ends of the treadles F, whereby motion is given to the harness G.

To the center of the batten, and on its front

face, is secured the hinged handle H, which the operator employs in communicating motion to the loom.

An adjustable hanger, I, is secured to the longitudinal rail of the frame A, and is slotted for the purpose of giving a lateral motion to the carrier D. The screw u, which secures it to the frame, is readily removed to permit the adjustment.

Upon the under side of the batten B is secured the spring l, which has its outer ends connected with the triggers C, for the purpose of returning the triggers, after they have been disengaged from the picker-sticks, to a position to again hold the sticks when they are pressed back.

The operator applies both hands to the handle H of the loom, draws the batten forward, when, in case the shuttle lands in either shuttle-box g, the detaining-arm m passes beneath the block n, entering the recess n'', which permits the full forward motion of the working parts of the machine; the post a of the batten having in the meantime engaged the front end, p, of the latch-bar C, which, in its motion toward the front, imparts to the cam s the desired rotary motion by means of the hook r engaging one of the pins s'. The finger-bar E is caused to advance from one treadle to another, and in this way motion is transmitted to the harness G. When the operator presses upon the handle H to give the backward motion to the batten, the post a strikes

the pin q in the latch-bar C, moving it back until the hook r engages the next pin s' of the cam s. Now, should the shuttle, which, when properly thrown, is retained in place in the shuttle-box g until the picker-block strikes it, from any cause whatsoever, be detained in its motion from one shuttle-box g to the other, the retaining-block h is not pressed out, and the detaining-arm m strikes the block n attached to the beam n', instantly notifying the operator that the process of weaving cannot be proceeded with until the necessary repairs shall have been made or the cause of derangement removed.

What we claim as new, and desire to secure by Letters Patent, is—

1. The sliding latch-bar C, having projections q and p, in combination with the posts a of the batten B and the ratchet-cam s, arranged and operating in the manner set forth.

2. The combination and arrangement of the spring l, constructed as described, with the lay-triggers and their operating-straps, as and for the purpose described.

3. The handle H, combined with the batten-top, in the manner described, and for the purpose specified.
